UNITED STATES PATENT OFFICE.

JAROSLAV VANCL, OF POLICEN, CZECHO-SLOVAKIA.

BUILDING SET.

Application filed September 9, 1920. Serial No. 409,271.

To all whom it may concern:

Be it known that I, JAROSLAV VANCL, a citizen of Czecho-Slovakia, residing at Policen, Met., Czecho-Slovakia, have invented 5 new and useful Improvements in Building Sets, of which the following is a specification.

The present invention relates to building sets, consisting of sheet metal strips, ties, 10 angles and the like which can be suitably connected to each other by means of hooks and eyes and such like to form toys of various kinds.

The accompanying drawings show in Figures 1 to 8 some constructional examples of the sheet metal strips or elements of the building set according to this invention.

Fig. 1 shows two of the elements in side view.

20 Fig. 1^a is a longitudinal section of one of the elements shown at Fig. 1.

Fig. 2 is a perspective view of an element with a portion of a second element shown connected thereto.

25 Fig. 3 shows a pair of similar elements with a third element connecting them with each other.

Fig. 4 is a perspective view showing two members connected to each other at right 30 angles.

Fig. 5 is a view similar to Fig. 4 showing a different method of connecting the same members.

Fig. 6 is a perspective view of another 35 form element.

Fig. 7 is a perspective view of an angle member with a portion of an element connected thereto at right angles.

Fig. 8 is a side view and cross section of 40 a number of the elements assembled together.

Fig. 9 shows as an example a roundabout, which can be constructed from the elements of the set.

45 Fig. 9^a is a partial plan view of the roundabout, and

Fig. 10 shows a wheelbarrow.

The elements of the building set mainly consist of sheet metal strips or ties or sheet 50 metal angles. The strips, ties and angles consist of stamped up and bent out strips of sheet metal provided with eyes and (or) hooks. In Figure 1 is shown a tie *a* provided adjacent its ends with hooks *c* and is 55 shown hooked into eyes *g* of a tie *m* shown in longitudinal section in Fig. 1^a. The hooks

c of the ties *a* may also engage in the manner shown in Figs. 2 and 3, the ties being thus connected together at a right or acute angle. The ends of the ties may also be bent 60 over at right angles and may be cut out in the shape of a fork, so that prongs *e* are formed, as on the element *f* (Fig. 2), and on the element *d* (Figs. 4, 5 and 7) and *h* (Figs. 6 and 8). Both hooks or prongs *c* and 65 eyes *g* may be formed on one and the same element, as for example the element *f*, Fig. 2, and *z*, Fig. 9. The angle pieces *h* are adapted to be used principally as eye pieces, the eyes *g* being stamped out either on one 70 side only as in Fig. 3, or on both sides of the angle as shown at Figs. 7 and 8. Two angular elements *h* connected to each other form a hollow rectangular column (see Fig. 8), and short elements *h* (which if desired 75 may be laid crosswise over each other) form the ends and are adapted to close the column. It is also important that the hooks *e* and also the eyes *g* are of such dimension that the openings *b* of the hooks correspond 80 accurately to the width of the eyes (see Figs. 3 and 8), the length of the eyes *g* being equal to the width of the ties (see Figs. 5 and 7) and the slot formed by them equal to the thickness of the ties (see Figs. 5 and 7) so 85 that a secure connection of the parts which are hooked into each other is thus ensured. The ties may be permanently bent into any desired form or may be made of spring sheet metal so that they may be bent according to 90 requirements.

The building set also includes various rods, shafts, wheels and the like, which may serve as supplementary parts in the construction of various toys.

95 As constructional examples of the toys which can be constructed according to the present invention a roundabout is shown at Figs. 9 and 9^a and a wheelbarrow at Fig. 10. When assembling the roundabout the 100 method adopted is as follows:

First the small lower column *h* is put together from angle pieces *l*, closing pieces *k* (as in Fig. 8) and ties *a* and *z*. Circular frames *r* and *s* formed out of bent ties are 105 then added and the whole is stiffened by means of ties *d* and connected to the second column *p*. The framework for the roof is then built up from ties *u* which are similar to the ties *a* but have additional hook parts. 110 The ring so produced is then mounted on the rod *v*, which latter is mounted in the column

h so that it can rotate. The swings are then hooked into the frame s by means of wires or the like as shown at Fig. 9.

The wheelbarrow illustrated at Fig. 10 is assembled in a somewhat similar manner from ties m having eyes and ties a and d having hooked ends, the bent ends of the ties d engaging intermediate eyes in the ties a. To the framework formed by these ties is then added a suitable U-shaped strip or member w having bearings for carrying the wheel y in such a manner that the said wheel can rotate in a position intermediate the arms of said U-shaped member. Two elements d¹ of somewhat greater length than the ties d constitute the horizontal arms or shafts of the wheelbarrow and these elements d¹ are held in a parallel position by means of transverse dies d²; the bent ends of the ties d² engaging intermediate eyes g¹ in the elements d¹.

What I claim is:—

1. A building set for toys comprising metal strips of various lengths and having eyes formed thereon by cutting and bending out portions of said strips, and similar metal strips having suitable hooks formed on the ends thereof for engaging the eyes of the first mentioned strips.
2. A building set for toys comprising strip metal pieces and metal angle pieces of various sizes some of which are provided with eyes formed thereon, each eye being formed by two parallel cuts extending in a longitudinal direction, the portion of metal intermediate said parallel cuts being stamped up or bent out to form a slot like aperture, the remainder of said pieces being provided with suitable hooked portions formed on the ends thereof for engaging the said eyes of the first mentioned pieces.
3. A building set for toys comprising metal strips of various lengths having eyes

formed thereon, metal strips of various lengths having hooks formed thereon adapted to engage the eyes of the first mentioned strips, and angle pieces each formed by a strip of metal having its end portions bent up into a position substantially at right angles to the plane of the said angle piece, the said bent up portions each having an open ended slot cut therein to form an interlocking hook.

4. An element for toy building comprising a strip of metal having eyes formed thereon each eye being formed by two parallel cuts extending in a longitudinal direction the portion of said element intermediate said parallel cuts being stamped up to form a slot like aperture.

5. An element for toy building comprising a strip of metal having its end portions bent up into a position substantially at right angles to the plane of said strip, said bent up portions each having an open ended slot cut therein to form hooked end portions, and eyes formed intermediate said hooked end portions each of which are formed by two parallel cuts extending in longitudinal directions the portion of said element intermediate said parallel cuts being stamped up to form a slot like aperture.

6. In a building set for toys, elements comprising strips of metal having bent-up end portions and further elements comprising strips of metal having slot like apertures of a width corresponding to the thickness of the bent-up portions of the first mentioned elements.

In testimony whereof I affix my signature in presence of two witnesses.

JAROSLAV VANCL.
